FRANK M. PEREZ, OF BROOKLYN, NEW YORK, ASSIGNOR, BY MESNE ASSIGNMENTS, TO
DAVID BRODY, OF NEW YORK, N. Y.

RECEPTACLE FOR DISPLAY.

1,313,906.

Specification of Letters Patent. Patented Aug. 26, 1919.

Application filed March 31, 1917. Serial No. 158,970

To all whom it may concern:

Be it known that I, FRANK M. PEREZ, a citizen of the United States, residing at Brooklyn, in the county of Kings and State of New York, have invented certain new and useful Improvements in Receptacles for Display, of which the following is a specification.

I have invented an improvement in receptacles; particularly a box which can be made of pasteboard, or some other suitable material, and utilized for the purpose of exhibiting merchandise to prospective purchasers.

The primary object of my invention is to provide a box comprising a body and a hinged lid or cover; the latter being adapted to support the body in such position as to present the contents advantageously to view, and bearing a display portion designed to assume and maintain a more or less upright position when the cover is performing its supporting function, and thus be utilized as a show card to bear advertising matter and attract a person's attention.

The above and other objects and advantages of my invention will appear from the following description, taken in connection with the accompanying drawings; which illustrate several embodiments of my invention. This disclosure, however, is explanatory only; and I reserve the right to resort to embodiments other than those actually illustrated herein; to the full extent indicated by the general meanings of the terms in which the claims are expressed, and by variations in the phrasing of the same.

On the drawings:

Figure 1 is a top view of my improved box with its cover in closed position;

Fig. 2 is a side elevation of the box or receptacle set up on exhibition;

Fig. 3 is a rear view of the box as seen in Fig. 2;

Fig. 4 shows a blank out of which my improved box can be made; and

Fig. 5 shows in perspective a modification of the box illustrated in the preceding figures.

The same reference characters identify the same parts throughout.

My improved box comprises a body 1 and a cover 2. The body 1 has a bottom 3 with sides 4 and ends 5; the cover 2 being hinged to the rear end 5 so as to be permanently

connected to the body, whether the cover is closed or open. When the box is used for storage or shipment, the cover rests upon the top of the merchandise in the box, and its edges may be inside the sides 4 and front end 5. To set up the box in display position, the cover is first turned upward and then downward, so that it extends across the plane of the bottom of the box; whereby the rear end of the body will be elevated, and the body thus supported at an incline, forward. Hence, the goods in the box will be presented to view.

As seen in Fig. 1, the cover 2 is provided with a transverse fold line between its hinged end and the opposite or free end. This fold line is indicated by the numeral 6; and the portion between the fold line and the free end of the box is adapted to be folded under the box, when the body thereof is to be displayed, as in Figs. 2 and 3. The distance between this fold line and the hinged end of the cover will, of course, be great enough to enable the cover to support the body at such a height as is necessary to cause the body of the box to be elevated to the required degree.

Inside the periphery of the cover I provide a display portion in the form of a cut-out section 7. To do this, the cover is cut through adjacent its sides and free end, and the cut-out section 7 will thus begin preferably at the hinged end of the cover, and will extend out as far as required. This cut-out portion 7, which serves as a show card, may, of course, have any suitable size or shape, and the width of the peripheral portion of the cover between the show card at any point and the adjacent edge of the cover may be relatively wide or relatively narrow; but it will, of course, be wide enough to give the cover the strength needed to carry the body of the box and the weight of the contents. This cut-out section 7 may extend beyond the fold line 6; but the latter does not pass across the portion 7, because the portion 7 is not to be folded or creased, but must assume a substantially upright position when the cover is turned down and under the box, as stated.

I may provide the free end of the cover with a projection 8 which is adapted to be inserted into a slot 9 in the bottom 3 of the body 1, and thus hold the cover and the body firmly together when the body is set

up. If desired, the peripheral portions of the cover may be strengthened by making the cover a greater length and width than the body of the box, and bending over the 5 edges so as to provide a double thickness of cardboard, or the like. The bent over edges, of course, may be glued or otherwise fastened in place.

The importance of the construction of my 10 improved box will now be apparent. So long as the goods are not to be put upon display the box may remain closed. When, however, the dealer wishes to exhibit the merchandise in the box, he lifts the cover 15 and folds it rearward and downward and under the body; at the same time raising the showcard so as to present its forward face to the front end of the box. The free end of 20 the cover will be secured to the bottom end of the box by virtue of the projection or tab 8; and the stiffness of the material of 25 which the box is made will be sufficient to retain the showcard in upright position. The show card 7 will bear suitable advertising matter, such as letters or figures, on its face, and will attract the buyers' attention, and both the box and its contents will thus be made conspicuous.

In practice the show card 7 need maintain 30 only a substantially upright position; since it will often incline backward to a greater or less extent. It will, however, always be held up to a sufficient degree to display the advertising matter on its face to 35 advantage.

A blank is made in one piece out of cardboard or the like for the purpose of forming my improved box, as shown in Fig. 3. This blank, in addition to the parts above 40 mentioned, includes extensions 10 at the extremities of the sides 4. These extensions have recesses extending into their edges adjacent the extremities of the front and rear ends of the box. The recesses are of such 45 shape as to provide tongues or projections 50 adapted to engage slots 12 in the ends 5.

The peripheral portions of that part of the blank for the cover 2, bordering the show card 7, are indicated by the numeral 55 13, and these portions have extensions 14 which can be doubled over on the peripheral portions 13 so as to provide two thicknesses of material out of which the blank is made, and thus strengthen the edges of the cover. 60 In order to hold the extensions 14 in contact with the portions 13, I may use fastening devices, such as staples, which are indicated at 65 Figs. 1 and 3. The tab or projection 8 is cut out of the extension 14 at the free end of the cover. This tab or projection may lie flat against the upper or outer face of the cover when the cover is closed; and afford a hold for one's hand when the cover is to be lifted. As shown in Figs. 1 and 4, the 85 tab 8 may have divergent sides, and may be

provided with parallel longitudinal score lines 16. These score lines permit the points at the outer ends of the tab to be folded over so as to facilitate the insertion of the tab into the slot 9 when the box is set up, 70 as in Fig. 2. After the tab is inserted into the slot in the bottom 3 of the box, the points can be turned away from folded position, and the tab thus prevented from becoming disengaged. The width of the tab between the 75 score lines 16 will be about equal to the length of the slot 9; but the greatest width of the tab along its outer or free edge will be in excess of the length of the slot 9. Therefore, when the points at the outer end 80 of the tab are folded, and the tab pushed through the slot 9, and the points then turned away from folded position back into the plane of the tab, the tab cannot be withdrawn, as will be understood. 85

As shown in Fig. 1, the cover when closed is engaged around its edges by the inner faces of the sides 4 and 5. If desired, I may make the cover large enough to rest upon the top edges of the sides 4 and 5, and provide it with sides and end flanges to extend down below the upper edges of the sides 4 and 5. The show card 7, as illustrated in Fig. 4, is provided by making a continuous cut from the hinge line between the rear end 95 5 and the cover 2, along one side of the cover, to a point adjacent the outer end of cover, then crosswise to the other side of the cover, and then back to the hinge line. I may also provide this section by making a 100 series of cuts instead of one continuous cut in the same way. Such a method is shown in Fig. 1. The successive cuts are separated by short uncut portions of box material which serve as stays and hold the show card 105 in the plane of the portions 13. This construction enables the box to be more securely closed by the cover when used for storage or shipment. When the box is to be set up, however, the dealer breaks out the show card 110 with his fingers by pressing upon the show card at the points between the successive cuts, which delineate it. This causes the bits of box material between the successive cuts to give way, freeing the show card and 115 producing the same effect as in Fig. 4. The method of providing the show card illustrated in Fig. 1 is to be employed when the cover is to be provided with side and end flanges to fit down over the outer faces of 120 the sides and ends, as already stated. When present, such side flanges will extend from the free end of the cover toward the hinged end, as far as the fold line 6 only, and the end flange will run entirely across the cover. 125 The side flanges may be given such shape as to enable them to coöperate in setting up the box when the cover is bent under the box, as in Fig. 2.

In Fig. 5 I show a modified box wherein 130

the fold line 6, the tab 8 and the extensions 14 are dispensed with. The cover 2 is designed to be turned backward and downward without being folded under the box; and it supports the box in display position by acting as a sort of prop. The edges of this cover are engaged by reinforcing members 17, which may be of metal, and which are doubled lengthwise to receive the edges of the cover and hold the same. These reinforcing members will, of course, be bent to a sufficient extent to grip the cover 2 securely. When the cover is folded back into supporting position, it may be engaged by a tongue 18, which is cut from the bottom of the box and is provided with a hook at its outer end to engage the lower part of the cover and prevent the same from slipping. The show card 7, when this type of box is set up, will maintain its upright position in the usual way.

Of course, the show card 7 may have various shapes according to the wish of the user and the design of advertising matter which it is to carry on its front face. In Fig. 5 the show card is somewhat smaller than the space inclosed by the remaining portion of the cover; and if desired, the cover may have a sheet of gelatin secured to its inner face, that is, the face presented to the observer. When this form of cover is closed, the gelatin will overlie the show card 7, and the contents will be shielded and protected, although they will not be entirely concealed.

Having described my invention, what I claim to be new, and desire to secure and protect by Letters Patent of the United States is as follows:—

40 1. A receptacle comprising a body and a cover hinged to one end thereof, the cover being adapted to be turned down across said end, and to be folded about a transverse line beneath the body, the portion between said line and the hinged end of the cover being longer than the depth of the body, whereby said portion may elevate said end of the body and support the body in display position.

50 2. A receptacle comprising a body and a cover hinged to one end thereof, the cover being adapted to be turned downward across said end and to be folded about a transverse line beneath said body, the portion of the cover between said line and the hinged end of the cover being longer than the depth of the body, whereby said portion may elevate the said end of the body and support the body in display position, and means carried by the free end of the cover to engage the body.

60 3. A receptacle comprising a body and a cover hinged thereto, the cover bearing a display portion, the cover being adapted to be turned so as to extend across the plane

of the bottom of the body to support the body in display position, the display portion being adapted to be maintained substantially upright when the body is in display position, the cover having reinforcing strips for the edges of the same, and means for enabling the cover and the body to be secured to each other when the body is in display position.

4. A receptacle comprising a body and a cover hinged to one end thereof, the cover having a cut-out section, the cover being adapted to be turned downward across said end and to be folded about a transverse crease beneath the body, the portion of the cover between said crease and the hinged end of the cover being longer than the depth of the body, whereby said portion may elevate said end of the body and support the body in display position, the cut-out section being adapted to be maintained substantially upright while the body is in display position.

5. A receptacle comprising a body and a cover hinged to one end thereof, the cover having a cut-out section, the cover being adapted to be turned downward across said end, and to be folded about a transverse line beneath the body, the portion of the cover between said line and the hinged end of the cover being longer than the depth of the body, whereby said portion may elevate said end of the body and support the body in display position, the cut-out section being adapted to be maintained substantially upright when the body is in such display position, and means for enabling the free end of the cover and the body to engage each other.

6. A receptacle comprising a body and a cover hinged thereto, the cover having a cut-out section, the cover being adapted to be turned so as to extend across the plane of the bottom of the body to support the body in display position, the cut-out section being adapted to be maintained substantially upright when the body is in display position, the cover having reinforcing strips for the edges of the same, and means for enabling the cover and the body to be secured to each other when the body is in display position.

7. A receptacle comprising a body and a cover hinged to one end thereof, the cover being adapted to be turned down across said end, and to be folded about a transverse line beneath the body, said line being located between the ends of the cover at such a point that it will be below the bottom of the body when the cover is turned to extend across said end of the body.

8. A receptacle comprising a body and a cover hinged to one end thereof, the cover being adapted to be turned downward across said end, and to be folded about a trans-

verse line beneath said body, said transverse line being located between the ends of the cover at such a point that it will be below the bottom of the body when the cover is turned across said end of the body; and means for enabling the cover and the body to engage each other when the cover extends across said end of the body.

9. A receptacle comprising a body and a cover hinged to one end thereof, the cover bearing a display portion, the cover being adapted to be turned downward across said end, and to be folded about a transverse line beneath the body, said line being located between the ends of the cover at such a point that it will be below the bottom of the body when the cover extends across said end of the body, the display portion being adapted to maintain a substantially upright position when the cover extends across said end of the body.

10. A receptacle comprising a body and a cover hinged to one end thereof, the cover bearing a display portion, the cover being adapted to be turned downward across said end, and to be folded about a transverse line beneath the body, said line being located

between the ends of the cover at such a point that it will be below the bottom of the body when the cover extends across said end of the body, the display portion being adapted to maintain a substantially upright position when the cover extends across said end of the body, and means for enabling the cover and the body to engage each other when the cover extends across said end of the body.

11. A receptacle comprising a body and a cover hinged to one side thereof, the cover being adapted to be turned downward across said side and to be folded about a transverse line beneath said body, the portion of the cover between said line and the hinged end of the cover being longer than the depth of the body, whereby said portion may elevate the said side of the body and support the body in display position, and means carried by the free end of the cover to engage the body.

In testimony whereof, I have signed my name to this specification, this 29th day of March, 1917.

FRANK M. PEREZ.
